YARD HYDRANT HEAD

Noel M. Anderson, P.O. Box 392,
Storm Lake, Iowa 50588

Filed July 15, 1970, Ser. No. 23,962

Term of patent 14 years

Int. Cl. D23—01

U.S. Cl. D23—32

FIG. 1 is a side view of a yard hydrant head showing my new design,

FIG. 2 is a front view thereof,

FIG. 3 is a rear view thereof,

FIG. 4 is a bottom view thereof,

FIG. 5 is a top view thereof, and

FIG. 6 is a perspective view thereof showing the hydrant standpipe and valve housing in broken lines for illustration only.

I claim:

The ornamental design for a yard hydrant head, as shown and described.
